CLAIM

The ornamental design for a vehicle body as shown and described.

DESCRIPTION

FIG. 1 is a front, top, left side perspective view of a vehicle body showing the new design;

FIG. 2 is a rear, top, right side perspective view thereof;

FIG. 3 is a top plan view thereof;

FIG. 4 is a left side elevation view thereof;

FIG. 5 is a right side elevation view thereof;

FIG. 6 is a front elevation view thereof; and,

FIG. 7 is a rear elevation view thereof.

The broken lines illustrate features of the vehicle body that form no part of the claimed design.

1 Claim, 6 Drawing Sheets
